UNITED STATES PATENT OFFICE.

ROBERT T. PARISEN, OF KNOXVILLE, PENNSYLVANIA, ASSIGNOR TO LAWSON MANUFACTURING COMPANY, OF HOMESTEAD, PENNSYLVANIA, A CORPORATION OF PENNSYLVANIA.

GAS-BURNER.

1,116,912.

Specification of Letters Patent. Patented Nov. 10, 1914.

Application filed May 14, 1914. Serial No. 838,486.

To all whom it may concern:

Be it known that I, ROBERT T. PARISEN, a citizen of the United States, and resident of Knoxville, in the county of Allegheny and State of Pennsylvania, have invented certain new and useful Improvements in Gas-Burners, of which the following is a specification.

While the present invention relates to a gas burner which is adapted for various uses, it has particular reference to the requirements of a burner for instantaneous water heaters wherein it is desired to produce perfect combustion from a relatively large flow of gas such as prevails during the intermittent periods when the burners of such heaters are active. The simple and highly efficient construction in which the invention is embodied provides for effectually separating the gas emitting portion of the delivery chamber from the portion thereof in communication with the mixer or receiving chamber, thereby eliminating back firing, and this is accomplished without harmful restriction of the gas emitting space so that there is ample provision for a copious flow to the burner orifices.

The invention is further directed to those structural features of the burner which provides for ready insertion of the perforate diaphragm and for affording quick and convenient access thereto for removal or other purposes.

In the accompanying drawings, Figure 1 is a vertical central cross-section of the improved burner. Fig. 2 is a view of the burner with one-half thereof in front elevation and the other half in longitudinal section. Fig. 3 is an end view of the discharge chamber with the diaphragm in position and with the closure cap removed.

Referring to the drawings, 2 designates a conventional form of burner body which encloses a fuel-receiving or mixing chamber 3 having at its lower end the usual gas connection 4 and the air inlets 5.

Formed integral with the upper end of body 2 is the horizontally elongated discharge chamber 6 having its interior of substantially circular form about a horizontal axis. Chamber 6 is open at its opposite ends at 7, and these openings are smaller than the chamber interior which results in the formation of flanges 8 which form the end walls of the gas emitting space 9 of the de-

livery chamber. At opposite sides of the lower portion of the interior of chamber 6 are the longitudinal abutment-forming ribs 10 which extend from end to end of the chamber and which are adapted to receive the longitudinal edges of the upwardly arched perforate diaphragm 11 which separates the gas emitting space 9 from portion 12 of the delivery chamber which is in communication with receiving chamber 3. The diaphragm is adapted to be entered through either end opening 7 with its extremities bearing against the end flanges 8, and this feature together with the engagement of the diaphragm edges with abutments 10 effectually separate the chamber spaces 9 and 12.

With the diaphragm in position, the opposite ends of the discharge chamber are closed by the cap-like devices 13. Each cap is formed with a central inset portion 14, and one of these insets is adapted to receive the head 16 of a tie bolt 15 and with the depression of the other cap receiving the nut 16'. This construction affords ready access to the burner interior and by means thereof the diaphragm may be readily inserted or removed.

The gas is emitted from space 9 at the exterior of diaphragm 11 through a plurality of apertures 17 in the wall of chamber 6, these apertures extending from end to end of the chamber and providing for a copious outflow of properly mixed air and gas, ample supply therefor being available from the relatively large discharge space 9, so that when the burner is in operation there is no retarding or choking tendency. Apertures 17 are protected from dripping condensate by the lip-like guard 18 formed integrally with the top of chamber 6 and extending from end to end thereof and so inclined as to overhang the burner apertures, as clearly shown in Fig. 1.

The construction of the burner is simple and inexpensive, chambers 2 and 6 and the diaphragm-holding means being embodied in a single casting, the only separate or separable parts being the diaphragm itself and the end closing caps and tie bolt.

I claim:

1. In a gas burner, the combination of a fuel-receiving chamber, a horizontally elongated open-end discharge chamber communicating with the receiving chamber and

formed with gas emitting apertures, a perforate diaphragm adapted to be entered through the open end of the chamber and separate the gas emitting portion of the chamber from the portion thereof in communication with the receiving chamber, and end-closing means for the discharge chamber.

2. In a gas burner, the combination of a fuel-receiving chamber, a horizontally elongated discharge chamber in communication with the receiving chamber and having its upper portion formed with gas emitting openings, and a horizontally elongated diaphragm within the discharge chamber and spaced from the top and opposite sides thereof with the portion of the chamber at the exterior of the diaphragm in free communication with the gas emitting openings and the portion of the chamber at the inner side of the diaphragm in unobstructed communication with the receiving chamber, and abutments at opposite sides of the lower portion of the discharge chamber adapted 25 to be engaged by the longitudinal edges of the diaphragm.
3. In a gas burner, the combination of a fuel-receiving chamber, a horizontally elongated discharge chamber having its interior 30 substantially circular about a horizontal axis and with gas emitting apertures in the upper portion of the chamber, and a transversely curved perforate diaphragm within and spaced from the inner face of the discharge chamber and forming an elongated transversely curved space which is in free communication with the gas emitting apertures and with said space separated from the portion of the chamber which 35 communicates with the receiving chamber.
4. In a gas burner, the combination of a fuel-receiving chamber, a horizontally elongated open-end discharge chamber having gas emitting apertures in its upper portion, 40 ribs extending longitudinally of the interior of the discharge chamber, a horizontally elongated perforate diaphragm adapted to be entered in the discharge chamber through its open end with the longitudinal edges of 45 the diaphragm engaging the ribs, the diaphragm separating the portion of the discharge chamber from which the gas is emitted from that portion which communicates with the receiving chamber, and end-closing 50 means for the discharge chamber.

5. In a gas burner, the combination of a fuel-receiving chamber, a horizontally elongated discharge chamber communicating with the fuel-receiving chamber and formed 55 with gas emitting apertures, the discharge chamber being open at its opposite ends and with the end openings smaller than the discharge chamber cavity, a perforate dia-

phragm extending from end to end of the discharge chamber with the ends of the diaphragm entered in the end openings of the chamber and thereby separating the gas emitting space at the exterior of the diaphragm from that portion of the discharge chamber which communicates with the receiving chamber, and means for closing the ends of the discharge chamber.

6. In a gas burner, the combination of a fuel-receiving chamber, a horizontally elongated discharge chamber in communication therewith and open at its opposite ends and formed with gas emitting apertures, longitudinal abutments within the discharge chamber at opposite sides thereof, a horizontally elongated perforate diaphragm 75 having its longitudinal edges in engagement with said abutments and thereby separating the gas emitting portion of the discharge chamber from the portion thereof which communicates with the receiving chamber, 80 and closing means for the end openings of the discharge chamber.

7. In a gas burner, the combination of a fuel-receiving chamber, a horizontally elongated discharge chamber in communication 90 therewith and open at its opposite ends and with the upper portion of the discharge chamber formed with gas emitting apertures, a perforate diaphragm adapted to be entered in the chamber through an end opening thereof and separating the gas emitting portion of the discharge chamber from the portion thereof which communicates with the receiving chamber, closures at the opposite open ends of the discharge chamber, 95 and a closure-connecting tie bolt extending through the discharge chamber.

8. In a gas burner, the combination of a fuel-receiving chamber, a horizontally elongated delivery chamber in communication 100 therewith and open at its opposite ends and having its upper portion formed with gas emitting apertures, a perforate diaphragm adapted to be entered through an open end of the discharge chamber for separating the gas emitting portion of the chamber from the portion thereof in communication with the receiving chamber, cap-like closures for the opposite ends of the delivery chamber, the closures formed with inset depressions, 115 and a tie bolt for the closures having its head entered in the depression of one closure and its nut in the depression of the other closure.

In testimony whereof, I affix my signature 120 in presence of two witnesses:

ROBERT T. PARISEN.
